DYEING SWAB

John Schifter, New York, N. Y.

Application June 9, 1932, Serial No. 616,205

9. Claims. (Cl. 132—12)

This invention relates to a swab which is particularly useful for dyeing hair.

One object of this invention is to provide a swab holder in which the swab part may readily be replaced.

Another object of this invention concerns the control of the width or thickness of the swab, so as to allow the dyeing of particular sections of strands of hairs.

10 Another object of this invention provides for retention of the dye in suitable retaining means of the holder, from where it may be fed to the swab, commensurate to the degree in which it is applied by the latter.

15 Other objects of this invention, which also concern the handiness and simplicity of construction of this device, will be more clearly understood from the accompanying drawing in which:

20 Fig. 1 shows the device of my invention in a side view.

Fig. 2 shows a corresponding top view.

Fig. 3 shows the side view of a modification of my invention.

25 Figs. 4 and 5 show transverse sections of the device of Fig. 3 in locked and unlocked positions, respectively.

Fig. 6 shows the side view of another modification of a device of my invention.

30 Fig. 7 shows a corresponding top view of part thereof.

Similar numerals refer to similar parts throughout the various views.

The device of Figs. 1 and 2 shows a frame 11 and a cover 12, the frame 11 comprises, first, a handle part 13, which is pointed at its rear end 14; it therefore permits the picking up of a strand of hair which is to be dyed; secondly, the swab holder part 15, which is offset vertically in respect to the holder part 11; in other words the swab holder extends beyond the fingers of the hand which holds the handle 11, so that the fingers holding the device are removed from the working plane.

45 From the holder part 15 laterally extend the threaded studs 16. The swab 17 which is made of felt, wick or some other suitable material, which may absorb a dye, is perforated so as to fit over the studs 16 and it is clamped upon the holder part 15 by the pressure of the nuts 19 which are tightened on top of the cover 12.

50 The swab 17 protrudes from the bottoms of the holder part 15 and the cover 12 which are in substantial alignment and which are toothed, as indicated by the teeth 18, the toothed part of the holder part and cover substantially matching each other, and serving to retain the swab between themselves, and to retain a reserve of dye. The swab 17 extends to such a distance 55 from the holder, that its narrow lower edge

may be observed by the hairdresser while the hair or root thereof is being dyed. At the same time it is close enough to the toothed ends of the holder part and cover that it is transversely held and restrained thereby and that it may draw from the reserve dye contained between the teeth, while the dye contained in the brush is being used up by application to the hair.

While the device of Figs. 1 and 2 allow an adjustment of the pressure exerted on the swab by means of the holder part and the cover, it may be desirable to avoid protruding parts like the nuts 19, which may interfere with free use and observation, and the hair may be caught thereon.

Devices modified in this respect are shown in Figs. 3, 4, and 5, and Figs. 6 and 7, respectively; these figures show the parts 11, 12, 13, 14, 15, 17 and 18, like Figs. 1 and 2; the studs 16, and nuts 19 are replaced in this instance by studs 20 with heads 21. These studs protrude from hubs which are of substantially the same diameter as heads 21 and which partly extend into the correspondingly sized openings in the swab 17. The heads 21 are spaced at such a distance from the holder part 15, that the swab 17 is suitably compressed between said holder part and the cover 12 when said cover is engaged in abutment underneath the heads 21. In the cover 12 are slots 23, which at their tops 25 allow passage of the heads 21, whereas they are narrower 30 at their lower ends 24, where they are only of a width accommodating the stud 20. When the dyeing swab of Figs. 3, 4 and 5 is assembled, the head 21 first registers with the part 25 of hole 23, and the lower ends of teeth 18 of cover 12 35 register with the bottom edge of the swab 17. The device is shown in this unlocked position in Fig. 4. But then the cover 12 is pushed up underneath heads 21, so that the studs 20 slide into the lower, narrower parts 24 of the slots and the lower ends of the teeth 18 of the cover as well as of the holder part come to register, the swab protruding from therebetween.

40 A depression 26 is provided in the cover 12, by means of which the cover may be engaged by 45 the nail of the finger, so that it can be conveniently pulled up from the position of Fig. 4 into that of Fig. 5.

The slots 23 may of course be horizontally 50 disposed in the cover 12 instead of being disposed therein vertically, in which latter instance the locking motion takes place horizontally.

55 A transverse locking motion also locks the device of Figs. 6 and 7.

The modification of these two figures does not comprise any studs, but there is an undercut recess 27 in the frame 11, between the handle portion and holder part thereof, into which a 60

laterally protruding tongue 28 of cover 12 may be inserted, the swab 17 being compressed between the cover and the holder part when the former is thus inserted in the frame. From the cover 12 extends a key 29, which fits into a suitable recess in the handle part above the recess 27, and which serves to guide the cover horizontally. Another lug 30 protrudes from the top of cover 12, said lug serving as a grip to the operator for shifting the cover transversely, during the locking and unlocking operations.

At the same time, when the tongue 28 is inserted in recess 27, the cover is pressed so hard down onto the swab 17, that a hook 31 extending from the other end of the cover engages underneath the holder part 15. In this manner I also show a tongue 32, which matches a recess in the back side of the holder part, and which corresponds in respect to its function to tongue 29.

The swab shows suitable openings in the two modifications, by means of which it is held in a correct position over the studs. The pins 33, indicated in Figs. 6 and 7, serve the same purpose. The device is assembled by placing the swab in the correct position on the holder part, the studs and pins holding it in such a correct position whereupon the cover is clamped onto the holder part in the manner shown in one or the other modifications of the drawing.

A shallow dish or trough contains the dye, which substantially fills the said container, so that the swab holder may be held substantially horizontal while the end of the swab protruding from the holder and the teeth of the holder are inserted in the liquid and engage upon a quantity thereof which is suitable for carrying on the dyeing operation for a certain period of time.

It is readily seen from the drawing that particular attention was given in the construction of the device of this invention to enhance the lightness so that the device may readily be manipulated and that the hairdresser may observe at all times the work performed with this device.

While I have shown and described my invention with some degree of particularity, it will be realized that other modifications and changes may be resorted to under special conditions. I therefore do not wish to be limited and restricted to the exact details shown and described, but reserve the right to make such changes and modifications as may fairly fall within the scope of the subject matter now being claimed.

What I claim is:—

1. A dyeing device for hair and beards comprising in combination, a pointed handle, a clamp integral with but longitudinally offset from said handle, a detachable clamp parallel with the integral clamp, a swab intermediate said clamps to retain and extrude pigment, and means to lock and release said swab relative to said clamps.

2. A dyeing device for hair and beards comprising in combination, a pointed handle, a toothed clamp integral with but offset in a substantially longitudinal plane with the handle, a detachable toothed clamp parallel with the inte-

gral clamp, a swab intermediate said clamps to retain and extrude pigment, and means to lock and release said swab and detachable clamp relative to the integral clamp.

3. A dyeing device for hair and beards comprising in combination, a pointed handle to facilitate the picking up of an individual hair, a toothed clamp integral with but offset in a substantially longitudinal plane with said handle, a recessed frame integral with the handle, a detachable toothed clamp one end of which registers with the recessed portion of the frame, a hook formed on the opposite end of said detachable clamp to engage the back of said integral clamp, a swab to retain and extrude pigment engaged intermediate said clamps, and means to lock and release said detachable clamp and swab relative to the integral clamp.

4. A dyeing device for hair and beards comprising in combination, a pointed handle to facilitate the picking up of an individual hair, a toothed clamp integral with but offset in a substantially longitudinal plane with said handle, a recessed frame integral with the handle, a detachable toothed clamp one end of which registers with the recessed portion of the frame, a hook formed on the opposite end of said detachable clamp to engage the back of said integral clamp, a swab to retain and extrude pigment engaged intermediate said clamps, means to lock and release said detachable clamp and swab relative to the integral clamp, and means to prevent transverse movement of the detachable clamp.

5. A dyeing device for hair and beards comprising in combination, a handle, a clamp integral and disposed in one plane with but longitudinally offset in said plane from said handle, a detachable clamp parallel with said integral clamp, a swab intermediate and protruding from said clamps, and means to lock and release said swab relative to said clamps.

6. A dyeing device for hair and beards comprising in combination, a pointed handle, a clamp integral with but longitudinally offset from the handle, a detachable clamp, a hydroscopic swab intermediate and protruding from said clamps, said swab serving as a means to retain and extrude pigments, and means to lock and release said swab and detachable clamp relative to the integral clamp.

7. In a hair dyeing device, a pair of coacting clamp plates, teeth comprised in said plates along corresponding sides thereof, and a swab engaged between said plates, an edge of said swab predeterminedly protruding from the points of said teeth in a straight unbroken line.

8. In a hair dyeing device, a pair of coacting clamp plates, teeth comprised in said plates along corresponding sides thereof, and a swab engaged between said plates, said swab extending to a predetermined distance from a plurality of sides of said plates.

9. In a hair dyeing device, a pair of coacting clamp plates, teeth comprised in said plates along corresponding sides thereof, and a swab engaged between said plates, substantially parallel edges of said swab extending to a predetermined distance from opposite sides of said plates.

JOHN SCHIFTER.
